UNITED STATES PATENT OFFICE.

MARSHALL B. GARDNER, OF AURORA, ILLINOIS, ASSIGNOR TO INTERNATIONAL CORSET COMPANY, OF AURORA, ILLINOIS, A CORPORATION OF ILLINOIS.

CORSET-CLASP.

1,317,698.

Specification of Letters Patent.

Patented Oct. 7, 1919.

Application filed April 15, 1918. Serial No. 228,525.

To all whom it may concern:

Be it known that I, MARSHALL B. GARDNER, a citizen of the United States, and a resident of Aurora, in the county of Kane 5 and State of Illinois, have invented certain new and useful Improvements in Corset-Clasps; and I do hereby declare that the following is a full, clear, and exact description thereof, reference being had to the accompanying drawings, and to the characters of reference marked thereon, which form a part of this specification.

This invention relates to improvements in corset clasps and has for its object a construction which will so hold the stays of the corset to which the two parts of the clasp are attached, as to prevent tilting or buckling of the stays, the gaping resulting therefrom and the unfastening.

These and other objects and advantages of my invention will appear as I proceed with my specification.

The invention consists of the matters hereinafter described and more particularly 20 pointed out in the appended claims.

In the drawing:

Figure 1 illustrates a fragmentary part, in front elevation, of the two front corset stays, with the clasp parts applied, showing 30 the two parts of the clasp in position as they appear when being engaged or disengaged.

Fig. 2 is a transverse, sectional view of the same in the plane indicated by the line 2—2 of Fig. 1.

Fig. 3 is a view similar to Fig. 1, showing the two parts of the clasp in position when the attachment is completed.

Fig. 4 is a transverse, sectional view of the same, taken in the plane indicated by 40 the line 4—4 of Fig. 3.

Fig. 5 is a transverse, sectional view of one member of the corset clasp taken in the plane indicated by the line 5—5 of Fig. 3.

Fig. 6 illustrates a modification of one of 45 the corset clasp members, showing the two parts of the clasp in position as they appear when being engaged or disengaged.

Fig. 7 is a transverse, sectional view of the same, in the plane indicated by the line 50 7—7 of Fig. 6.

Fig. 8 is a view similar to Fig. 6, showing the two parts of the modified form of clasp in position when attachment is completed.

Fig. 9 is a transverse, sectional view of

the modified form, in the plane indicated by 55 the line 9—9 of Fig. 8.

Fig. 10 is a longitudinal, sectional view of the modified clasp member shown in Fig. 6, in the plane indicated by the line 10—10 of Fig. 6.

Referring now to Figs. 1 to 5, inclusive, A indicates a front corset stay and B a second and adjacent front corset stay. To these two stays or strips are attached a plurality of clasp members embodying my invention.

In each instance, the clasp comprises two parts, a stud member 1 attached to one of the front stays or stiffening strips, and an eyelet member 2 attached to the other stiffening stay or strip member. The stud member 1 has a body portion 3 provided at one end 70 with a rivet shank 4 and at the other end with a head 5, the lower portion of the head being squared off to afford a shoulder 6. The rivet shank affords means by which the 75 stud member may be firmly attached to the corset stay or strip A.

The eyelet member 2 is attached to the corset stay or strip B by rivets 7, or other suitable means, and said eyelet member 2 is 80 a relatively thin metal plate, fashioned as shown. It is provided with a longitudinally arranged keyhole aperture therethrough, comprising a comparatively large slot or hole 8 at one end and a relatively smaller 85 and narrower one 9, at the other end,—the holes 8 and 9 opening into each other to form a keyhole shaped slot or aperture. The diameter of the part 8 of this aperture is appreciably larger than the diameter of 90 the head 5 of the stud member 1. The width of the narrower opening 9 is substantially the same as the diameter of the body portion 3 of the stud member 1.

By means of a stamp mill or by other suitable mechanism, a portion of the eyelet member 2 is raised upwardly from the outer or top face of the plate so as to form raised bearing or supporting surfaces 10 for the shoulder 6 of the stud head 5, there being 100 two of such supporting shoulders 10, one on either side of the slot 9.

That portion of the plate 2 constituting the raised part which terminates in the shoulders 10, is cone-shaped or conical, as is 105 clearly shown in Figs. 1 and 2, thus giving great strength and rigidity to the supporting shoulders 10. It will be observed by

reference to Figs. 1 and 2, also, that the portions of the plate constituting this conical or raised surface on either side of the slot 9, are joined together at the end of said slot 5 9 by an upwardly extending flange portion 11, which further increases the strength and rigidity of the supporting shoulders 10.

The operation of my improved clasp when constructed as described, will be as follows:

- 10 When the eyelet and stud members are attached to their respective stays and the stays themselves affixed in the usual way to the corset body, each set of clasp members, 1 and 2, may be engaged, first one and then 15 the other, down the length of the corset body. This is done by first inserting the head 5 of the stud member through the opening 8 of the eyelet member. The stud is then drawn either by the hand of the wearer 20 or by the natural expansion of the body of the wearer of the corset, through the key-hole aperture and toward and between the parallel sides of the narrower slot member 9. As the body 3 of the stud member is thus 25 being drawn home, to the limit of the movement,—that is, toward the flange 11 at the end of the opening 9, of the eyelet member, the stud member is pressed in an upward direction, sufficiently to enable the shoulder 30 6 on the under side of the head 5 of the stud, to rest upon the supporting shoulders 10, 10, of the eyelet member 2. In assuming this position, the edge of the head 5 of the stud member, will easily ride upon the inclined 35 or conical wall surfaces 12 (see Fig. 2), and then readily slip into position on the top of the shoulders 10, as more clearly seen in Fig. 4. The shoulders 10 taper away or are inclined downwardly to a slight degree, 40 toward the front of the slot 9, as more clearly shown in Figs. 2 and 4, so that when the stud member 1 is in the final position of engagement, the said supports 10 extend under and contact only with a portion of the 45 shoulder 6 of the stud head.

In this position, the eyelet member 2 and the stud member 1 will be firmly and securely locked together, in such manner as not only to prevent any rocking or tilting 50 movement of one corset stay with respect to the other, but also to prevent the corset stays from opening. The normal tilting tendency of the stud member 1, when in use, will be in the direction of the stay or corset strip 55 B, and as the pressed up or raised portions of the eyelet member 2 which constitute the supporting flanges 10, are higher on that side of the member 2 adjacent to the strip B, than on the opposite end of the member 2, 60 the tendency to tilt is of course instantly checked and tilting prevented.

The slight resiliency or play necessary to have between the clasp members is afforded by the slight inclination toward the 65 front in the direction away from the tilting

tendency of the stud and the supporting shoulders 10.

I have stated that the stud body 3 is substantially of the same diameter as the distance apart of the two shoulders 10, but it 70 will be understood, of course, that there will be the slightest amount of lateral play between the body member 3 of the stud and the two sides of the slot 9.

In pressing up the body of the eyelet member 2 to form the shoulders 10, 10, a chamber or recess 13 will be formed on the under side of the member 2 on either side of the slot 9. In this chamber or recess the head 5 of the stud member may be accidentally 80 or inadvertently inserted by the user when in the act of engaging the corset members 1 and 2. Lest the user should inadvertently believe that the members 1 and 2 are thus permanently secured and locked together, I 85 have provided a means for disengaging the head 5 from said recess 13, said means consisting of rounding or sloping the under surface 14 of the plate 2 at the forward end of said recess 13. By so doing, it will be 90 found that the rounded portion of the stud head 5 will almost immediately slip along and over this rounded surface 14, in the normal act of moving the stud 1 in the attempt to seat it home, or by the normal and natural 95 expansion of the body of the user of the corset; and thus the two parts 1 and 2 will be disengaged. The user will thus have her attention directed to this fact and will be careful in locking the two parts together, to 100 compress the stud 1 upwardly along the inclined surface 12 until the head 5 rests firmly upon the supporting shoulders 10, 10.

In the modification shown in Figs. 6 to 10, inclusive, I provide upturned flanges 15, 105 15, one on either side of the narrow slot or opening 9, each of which flanges has a sloping rear wall 16 and a somewhat downwardly inclined supporting shoulder 17, upon which shoulder the head 5 of the stud 110 member will rest. The sloping wall 16 will correspond with the sloping side wall 12 of the first form described, and function correspondingly; while the supporting shoulder 17 will correspond with the supporting 115 shoulders 10, first described, and function correspondingly.

This modified form possesses some advantages in cheapness over that first described, and also eliminates the recess 13 first described. 120

It will be manifest to those familiar with the art that the eyelet member 2 may be quickly and cheaply manufactured, in either form described, by stamping or otherwise, and that when shaped and fashioned in either form illustrated, the two parts of my improved corset will perform the function of preventing all tilting and buckling between the corset stays, and also will per- 125 130

form the additional function of preventing disengagement of the stays in the ordinary movement of the wearer.

My clasp has the additional advantage of 5 using stud members of the standardized and accepted shape and height, known to the corset makers as "high studs". The use of such stud members makes the engaging and disengaging of the two parts of the clasp 10 more readily accomplished by the wearer than where low or short studs are employed, but with the use of high studs, tilting, buckling and disengagement become more liable. With my invention, the height of the stud 15 member is no objection because the height thereof is compensated for by the distance of the supporting surfaces 10, 10, in the one form, and 17, 17, in the other form, from the top surface of the eyelet member 2. This 20 distance is such as to afford the necessary support and to cause an absolutely non-tilting, locking engagement of the eyelet member 2 between the top of the stay member A and the head of the stud member 1, when 25 the two parts are brought into juxtaposition by the user.

It will be observed more particularly by reference to Fig. 5 that the rounded head 5 of the stud member follows approximately 30 the contour of the conical walls of the support 10, so that in practical use there are no sharp corners or edges, but substantially 35 one continuous surface. Thus there is nothing upon which the garments of the 40 wearer of the corset are liable to catch and tear.

My device is simple, cheap to manufacture and easily manipulated by the user of a corset. It also possesses great utility.

40 I claim as my invention:

1. A clasp of the kind described, comprising a stud member provided with a flanged head, an eyelet member provided with a keyhole aperture therethrough adapted to 45 receive the stud member, raised-up integral surfaces on the eyelet member, one on either side of the keyhole aperture intermediate its ends, said surfaces being downwardly inclined and adapted to support the flanged 50 head of the stud member.

2. A clasp of the kind described, comprising a stud member provided with a flanged head, an eyelet member provided with a keyhole aperture therethrough adapted to 55 receive the stud member, raised up, integral,

downwardly inclined surfaces on the eyelet member, one on either side of the keyhole aperture intermediate its ends, adapted to support the flanged head of the stud member, and means adapted to be engaged by the head of the stud member to guide and facilitate the movement of the latter toward the raised support. 60

3. A clasp of the kind described, comprising a stud member provided with a flanged head, an eyelet member provided with a keyhole aperture therethrough adapted to receive the stud member, raised up, integral, downwardly inclined surfaces on the eyelet member, one on either side of the keyhole 65 aperture intermediate its ends, adapted to support the flanged head of the stud member, and means adapted to be engaged by the head of the stud member to guide and facilitate the movement of the latter toward 70 the raised support, said means comprising an engaging surface upwardly and outwardly inclined toward the said support. 75

4. A clasp of the kind described, comprising a stud member having a rounded head and a flange on the under side of the head, an eyelet member having a keyhole aperture therethrough adapted to receive the stud member, two conical wall integral surfaces formed in the eyelet member, one on 80 either side of the aperture and a downwardly inclined flange supporting shoulder on each of said surfaces. 85

5. A clasp of the kind described, comprising a stud member having a flanged and a rounded head, an apertured eyelet member, a raised up integral flange supporting shoulder, downwardly inclined, one on each side of said aperture, a recess in said eyelet member underneath said supporting shoulders, and means for disengaging the head from said recess when the stud head is inadvertently positioned therein, comprising the rounded downwardly and outwardly inclined surface 14 near the forward end of 90 95 said recess. 100

In testimony, that I claim the foregoing as my invention I affix my signature in the presence of two witnesses, this 11th day of April A. D. 1918.

MARSHALL B. GARDNER.
